UNITED STATES PATENT OFFICE

2,558,466

CONVERTIBLE ROCKER FURNITURE

Edward A. Simard and Raymond P. Simard,
Beecher Falls, Vt.

Application April 30, 1948, Serial No. 24,259

5 Claims. (Cl. 155—73)

1

This invention relates to improvements in rocker type furniture, and the primary object of the invention is to provide simple and inexpensive convertible rocker structure which can be readily incorporated in different kinds of furniture, such as kitchen, dining room, living room, porch, bedroom, and nursery furniture.

Another important object of the invention is to provide convertible rocker structure of the above indicated character which is self-concealing so as not to be visible in a manner to detract from the conventional or ornamental appearance of the piece of furniture in which it is incorporated.

Another important object of the invention is the provision of convertible rocker structure of the character indicated above of which a major portion constitutes a permanent structural component of the piece of furniture in which the structure is incorporated, and which effectively supports both in operative and inoperative positions the movable element of the structure and conceals the latter in its inoperative position.

Other important objects and advantageous features of the invention will be apparent from the following description and accompanying drawings, wherein for present purposes of illustration only, a specific embodiment of the invention is set forth in detail.

In the drawings—

Figure 1 is a side elevation of a convertible rocking chair embodying the invention, with the movable rocker in operative position.

Figure 2 is a similar fragmentary view, showing the movable rocker concealed in inoperative position.

Figure 3 is a fragmentary front elevation of Figure 1.

Figure 4 is a transverse vertical section taken on the line 4—4 of Figure 1, on an enlarged scale.

Figure 5 is a similarly enlarged transverse vertical section taken on the line 5—5 of Figure 2.

Figure 6 is a fragmentary bottom elevation of Figure 5, and,

Figure 7 is a perspective view of one of the movable rockers.

Referring in detail to the drawings, the invention is shown incorporated in a chair 8 comprising a seat 9 supported between and connected to sides 10, 10 each comprising a front vertical post 11 and a rear vertical post 12.

The convertible rocker structure comprises a rigidly mounted horizontal brace 14 having its front and rear ends tenoned or otherwise suitably fixed, as indicated at 15 and 16, respectively,

5 on the front and rear posts 11 and 12, respectively, of each chair side 10, the brace having a straight longitudinal lower edge 17, and an upwardly curved upper longitudinal edge 18 of the same curvature as that of a rocker runner appropriate for the chair 8. The lower edge 17 of the brace 14 is spaced upwardly from the lower ends of the posts 11 and 12 which, as indicated at 19, are oppositely curved to constitute extensions at 10 the opposite ends of the movable rocker 20 when in operative position, as shown in Figure 1.

15 The rocker 20 is of the same shape, size, and thickness as the brace 14, both being vertically elongated rectangular in cross section, as shown in Figures 4 and 5, the rocker having a straight edge 17' and a curved runner edge 18' corresponding to the edges 17 and 18, respectively, of the brace 14.

20 Concealed type hinges 21 having anchor portions thereof in recesses 22 in the straight edges 17 and 17', hingedly connect the brace 14 and rocker 20 together, so that the rocker 20 can be swung upwardly and inwardly to inoperative position, in which it occupies a position along the 25 laterally inward or inboard side of and is in registry with and is concealed by the companion brace 14, as shown in Figures 2 and 5; or swung downwardly and outwardly from such inoperative position, in which the chair 8 is supported on a floor 23 on the lower ends of its posts 11 and 12, to a position beneath and in full vertical alignment with the companion brace 14, as shown in Figures 1, 3 and 4, wherein the chair 8 is rockably supported on the floor 23 by the rocker runner edge 18', wherein the straight edges 17 and 17' 30 abut squarely, so as to resist inward displacement of the rocker 20, while outward displacement thereof is precluded by the arrangement of the hinges 21.

35 For releasably holding the rockers 20 in inoperative position while the chair is lifted from or shifted over the floor 23, and in operative position, snap connectors are provided, which comprise male elements 24 and 25 on the edge 17' of the rocker 20 and on the concealed side of the rockers 20 near the runner edges 18', respectively. 40 As shown in Figure 4, the male elements 24 are arranged to snap into female snap elements 24' socketed in the straight lower edges 17 of the braces 14 while, as shown in Figure 5, the male snap elements 25 are arranged to snap into the female elements 25' socketed in the upper part 45 of the inboard sides of the braces 14. Relatively small pressure or pull on the forward or rearward ends of the rockers 20 are required to separate or 50 55

engage the snap connectors or fasteners to permit quickly and easily positioning the rockers as desired.

As shown in Figures 5 and 6, the brace 14 and companion rocker 20 on each chair side when folded together form a body whose width is the same or less than that of the posts 11 and 12, so that the rocker structures are concealed from the front and back of the chair 8.

For concealing the tops of the rocker structures from view, a conformably curved plate or binding 26, at least as wide as the brace 14 and rocker 20 together when folded, extends lengthwise between the posts 11 and 12 and is secured, as indicated at 27, in Figure 5 upon the curved upper edge 18 of the brace 14 and projects laterally inwardly therefrom above the runner edge 18' of the rocker 20.

A finger hole 30 is provided in the rocker element 20 to facilitate manipulation thereof into and out of operative position.

What is claimed is:

1. A convertible rocker structure for a piece of furniture having a side involving front and back posts, said structure comprising a solid brace extending between and fixed to said front and back posts on a level above the lower ends of said posts, a solid rocker hinged to the lower edge of said brace to swing from an inoperative position along the inboard side of said brace to an operative position beneath said brace in which said rocker projects below the lower ends of said front and back posts to support the piece of furniture rockably on a horizontal surface with the lower ends of said front and back posts spaced above said surface, said brace and rocker being of the same size and shape and said rocker being arranged to register with said brace while in its inoperative position, so as to be concealed by said brace from a viewpoint at the outboard side of said piece of furniture.

2. A convertible rocker structure for a piece of furniture having a side involving front and back posts, said structure comprising a horizontal brace extending between and fixed to said front and back posts on a level above the lower ends of said posts, a rocker hinged to the lower edge of said brace to swing from an inoperative position along the inboard side of said brace to an operative position beneath said brace in which said rocker projects below the lower ends of said front and back posts to support the piece of furniture rockably on a horizontal surface with the lower ends of said front and back posts spaced above said surface, said brace and rocker together having a cross sectional width in the inoperative position of said rocker no greater than the widths of said front and back posts and being positioned therebehind so as to be concealed from viewpoints at the front and back of said piece of furniture.

3. A convertible rocker structure for a piece of furniture having a side involving front and back posts, said structure comprising a horizontal brace extending between and fixed to said front and back posts on a level above the lower ends of said posts, a rocker hinged to the lower edge of said brace to swing from an inoperative position along the inboard side of said brace to an operative

position beneath said brace in which said rocker projects below the lower ends of said front and back posts to support the piece of furniture rockably on a horizontal surface with the lower ends of said front and back posts spaced above said surface, said brace and rocker being of the same size and shape and said rocker being arranged to register with said brace while in its inoperative position, so as to be concealed by said brace from a viewpoint at the outboard side of said piece of furniture, and a concealment strip secured on the upper edge of said brace and projecting laterally therefrom in an inboard direction so as to overlie the corresponding edge of said rocker when in its inoperative position and conceal the upper edges thereof from a viewpoint thereabove.

4. A convertible rocker structure for a piece of furniture having a side involving front and back posts, said structure comprising a horizontal brace extending between and fixed to said front and back posts on a level above the lower ends of said posts, a rocker hinged to the lower edge of said brace to swing from an inoperative position along the inboard side of said brace to an operative position beneath said brace in which said rocker projects below the lower ends of said front and back posts to support the piece of furniture rockably on a horizontal surface with the lower ends of said front and back posts spaced above said surface, and releasable fastening means operating between said brace and said rocker for holding said rocker in its operative position comprising male elements on said rocker and female elements on said brace and in its inoperative position.

5. A side for a chair comprising a pair of vertical legs, a horizontal brace extending between and secured to the legs, said legs being substantially twice the thickness of said brace with said brace disposed toward the outer sides of the legs, a rocker of the same thickness as said brace positioned along the inward side of said brace and nested in the space between the legs unoccupied by said brace whereby said rocker is concealed from the outer side and from the front and rear of the chair, means releasably holding said rocker in the concealed position, hinge means connecting said rocker with the lower edge of said brace whereby said rocker can be swung downwardly and outwardly from a concealed position to an operative position in which said rocker is supportably engaged with the lower edge of said brace and depends below said legs, and means releasably holding said rocker in operative position.
